(57) **CLAIM**

The ornamental design for a re-closable bag with integrated finger sleeves, as shown and described.

DESCRIPTION

FIG. 1 is a perspective view of a first embodiment of a bag with integrated finger sleeves showing the top and front sides thereof, the bag illustrated in a first condition;

FIG. 2 is a perspective view of the bag of FIG. 1, showing the bottom and front sides thereof, the bag illustrated in a first condition;

FIG. 3 is a front plan view of the bag of FIG. 1, the bag illustrated in a first condition;

FIG. 4 is a rear plan view of the bag of FIG. 1, the bag illustrated in a first condition;

FIG. 5 is a perspective view of the bag of FIG. 1, showing the top, left, and front sides thereof, the bag illustrated in a second condition;

FIG. 6 is a perspective view of the bag of FIG. 1, showing the top, right, and rear sides thereof, the bag illustrated in a second condition;

FIG. 7 is a right side view of the bag of FIG. 1, the bag illustrated in a second condition;

FIG. 8 is a left side view of the bag of FIG. 1, the bag illustrated in a second condition;

FIG. 9 is a bottom side view of the bag of FIG. 1, the bag illustrated in a second condition;

FIG. 10 is a top side view of the bag of FIG. 1, the bag illustrated in a second condition;

FIG. 11 is a perspective view of the bag of FIG. 1, showing the top, left, and front sides thereof, the bag illustrated in a third condition;

FIG. 12 is a perspective view of the bag of FIG. 1, showing the bottom, right, and rear sides thereof, the bag illustrated in a third condition;

FIG. 13 is a perspective view of the bag of FIG. 1, showing the rear and left sides thereof, the bag illustrated in a fourth condition;

FIG. 14 is a perspective view of the bag of FIG. 1, showing the front and left sides thereof, the bag illustrated in a fourth condition;

FIG. 15 is a front plan view of the bag of FIG. 1, the bag illustrated in a fourth condition;
FIG. 16 is a rear plan view of the bag of FIG. 1, the bag illustrated in a fourth condition;
FIG. 17 is a right side view of the bag of FIG. 1, the bag illustrated in a fourth condition;
FIG. 18 is a left side view of the bag of FIG. 1, the bag illustrated in a fourth condition;
FIG. 19 is a perspective view of a second embodiment of a bag with integrated finger sleeves showing the top and front sides thereof, the bag illustrated in a first condition;
FIG. 20 is a perspective view of the bag of FIG. 19, showing the bottom and front sides thereof, the bag illustrated in a first condition;
FIG. 21 is a front plan view of the bag of FIG. 19, the bag illustrated in a first condition;
FIG. 22 is a rear plan view of the bag of FIG. 19, the bag illustrated in a first condition;
FIG. 23 is a perspective view of the bag of FIG. 19, showing the top, left, and front sides thereof, the bag illustrated in a second condition;

FIG. 24 is a perspective view of the bag of FIG. 19, showing the top, right, and rear sides thereof, the bag illustrated in a second condition;
FIG. 25 is a right side view of the bag of FIG. 19, the bag illustrated in a second condition;
FIG. 26 is a left side view of the bag of FIG. 19, the bag illustrated in a second condition;
FIG. 27 is a bottom side view of the bag of FIG. 19, the bag illustrated in a second condition;
FIG. 28 is a top side view of the bag of FIG. 19, the bag illustrated in a second condition;
FIG. 29 is a perspective view of the bag of FIG. 19, showing the top, left, and front sides thereof, the bag illustrated in a third condition; and,
FIG. 30 is a perspective view of the bag of FIG. 19, showing the bottom, right, and rear sides thereof, the bag illustrated in a third condition;
The broken lines are for environmental purposes only and form no part of the claimed design.
